ROTARY PISTON AIR PUMP

Alfred Bräm, Schlieren, Switzerland, assignor to
Micafl A.-G., Zurich-Alstetten, Switzerland

Application December 8, 1948, Serial No. 64,070
In Switzerland December 8, 1947

5 Claims. (Cl. 230—47)

1

The invention refers to a rotary piston air pump for use with gases and vapors, the pump being immersed in oil contained in a container and provided with at least one radially movable blade and an oil seal, as well as with an outlet having an exhaust valve arranged below the oil level in the container and with a second outlet means terminating in the atmosphere above the oil level.

Pumps of this type are often used for pumping damp vapors. Since the sealing oil inside the pump comes into close contact with the vapors, the oil becomes saturated and an emulsion is formed after a time. Generally, not all of the pump and casing parts have the same temperature, and heavy over-saturated oil collects and becomes stationary particularly in the relatively cool lower part of the container, so that condensate forms there. The condensate displaces the oil and disturbs the operation of the pump.

The object of the present invention is to prevent the super-cooling of stagnating oil portions and to relieve the oil of the damp vapors which are enclosed in it. According to the invention this is achieved by providing the pump with a device for introducing contaminated sealing oil from the lowest point of the container into the pump chamber. Flow of oil into the pump is assured by the low pressure in the chamber until it is connected with the pump outlet and the relatively high atmospheric pressure in the container. The condensate which is sucked into the chamber of the pump together with the sealing oil evaporates due to the lower pressure in the pump and, as the piston continues to rotate, the vapors and the oil are expelled through the exhaust outlet of the pump into the container. The vapors exhaust through a vent in the top of the container and the oil collects in the container.

Two constructional examples of the invention are illustrated in the accompanying drawing. Fig. 1 shows, diagrammatically, a rotary piston air pump according to the invention in section. Fig. 2 illustrates, diagrammatically, a modified pump according to the invention, also in section. Fig. 3 is a longitudinal large scale sectional view of a pump outlet valve.

In both examples the pump is built into a container *a* which is closed by a cover *b*, the container being filled with sealing oil up to the mark *c*. The piston or rotor *f* rotates about its axis inside the pump casing *e* in the direction indicated by the arrow. The two blades *g* together with the piston *f* and the wall of the casing *e* form a space *p* which is shut off from the suc-

2

tion pipe *i* and is termed the suction chamber. In this chamber *p* there is suction pressure, that is a pressure that is below that of the atmosphere. In accordance with the invention for this position of the piston, that is with each suction stroke, the suction chamber *p* is connected with the lowest point of the sealing-oil container *a*.

For this purpose it is an advantage to provide the container *a* with an inclined bottom. The connection between the suction chamber and the lowest point of the container *a* is achieved by means of a pipe *c* which is provided with a stop valve *r* for regulating the flow of oil.

The pipe *q* can either be arranged outside of the container *a* and connected to the lowest point of the latter as shown in Fig. 1, or the pipe *q* together with the valve *r* can be located inside of the container *a* as is illustrated in Fig. 2.

As long as the pressure in chamber *p* is below atmospheric pressure, contaminated oil from the bottom of container *a*, which is under atmospheric pressure, enters chamber *p* through conduit *q*. Due to the subatmospheric pressure in chamber *p*, the vapors contained in the oil are released therefrom. Both, oil and vapor, are expelled through outlet *l* into the air space *n* above the oil level *c*, and the vapor escapes through outlet *k*. For producing a higher vacuum outlet *l* is provided with a valve, not shown, which is closed so that the sealing oil is passed with the air through the additional outlet *m* which is disposed between the inlet *i* and the outlet *l* substantially at the place where the rotor *f* is tangent to the inside of the pump casing *e*. Outlet *m* is provided with a non-return valve shown in Fig. 3 and disposed below the oil level in container *a*.

I claim:

1. A rotary vacuum pump comprising, in combination, a container containing sealing oil and having an outlet to the atmosphere, a pump casing having a chamber disposed in said container and being submersed in the sealing oil, inlet means for the medium to be pumped connected with said chamber and extending outside of said container, outlet means for the pumped medium connected with said chamber and terminating in said container, a rotor eccentrically mounted in said chamber, pump blades radially movably fitted in said rotor along a diameter thereof and dividing the space in said chamber into a suction and a delivery portion, and a sealing oil supply conduit extending from substantially the lowest point of said container into the delivery portion of said pump chamber.

2. A rotary vacuum pump as defined in claim 1, comprising a regulating valve in said conduit.
3. A rotary vacuum pump as defined in claim 1, said sealing oil conduit being disposed within said container.
4. A rotary vacuum pump as defined in claim 1, said sealing oil conduit being disposed substantially outside of said container.
- combination, a container partly filled with oil
5. A rotary vacuum pump, comprising, in combination, a container partly filled with oil and having an outlet to the atmosphere, a substantially horizontal cylindrical pump casing having a chamber disposed in said container, a rotor eccentrically mounted in said chamber and being tangent to the upper portion of the inside of said casing, pump blades radially movably fitted in said rotor along a diameter thereof, inlet means for the medium to be pumped connected with the upper portion of said chamber at one side 15 of the part of the chamber where said rotor is tangent to said casing, outlet means for the pumped fluid connected with said chamber at the other side of the part of the chamber where said rotor is tangent to said casing and terminating 20 above the oil in said casing, a conduit having an inlet end disposed substantially at the lowest point of said container and having an outlet end connected with the upper portion of said chamber at the same side of the part thereof 25 where the rotor is tangent to said casing as where said outlet means is connected, for admitting

sealing oil into said chamber and for being at all times non-communicating with said inlet means, and an additional outlet means connected with said casing at the upper portion of the pump chamber between said inlet means and said first outlet means and substantially at the place where said rotor is tangent to said casing.

ALFRED BRÄM.
